UNITED STATES PATENT OFFICE.

WENZEL H. BOEHM, OF SWISSVALE, AND HOWARD S. COREY, OF PITTSBURGH, PENNSYLVANIA.

LIQUID-FUEL BURNER.

Application filed September 28, 1925. Serial No. 58,079.

This invention relates to liquid fuel burners for use in open-hearth furnaces and other industrial furnace, and more particularly adapted for burning tar, although other liquid fuels may be used.

One object of the present invention is to provide a burner of this type composed principally of standard pipe and fittings, whereby the first cost is greatly reduced, and repair parts are readily obtainable.

Another object is to provide a burner of this class having an improved construction whereby the fuel will be more thoroughly atomized than in the ordinary burners heretofore used.

A further object is to provide a burner having the novel arrangement, construction, and design of parts hereinafter described in detail and illustrated in the accompanying drawings.

In the drawings—

Figure 1 is a longitudinal elevation of a burner constructed in accordance with our invention, the water jacket being in section.

Figure 2 is an enlarged detail sectional elevation through the forward end of the burner.

Figure 3 is a sectional plan through the burner.

Figure 4 is a rear end elevation.

Figure 5 is a sectional plan taken on the line V—V of Figure 2.

Referring more particularly to the drawings, the letter A designates the water jacket as a whole, which is composed of inner and outer tubular spaced side wall members 2 and 3, respectively, provided with end wall members 4 and 5 in the form of cap pieces which are secured to the side wall members 2 and 3 by welding, as at 6. The inner wall member 2 is flattened so as to provide a greater space at the bottom and top than at the sides of the jacket. Water is supplied to the jacket A, under pressure, through a pressure pipe 7 which enters the jacket through an opening in the rear end wall or cap piece 5, and is welded thereto as at 8 to form a water-tight connection or joint. The pipe 7 extends forward along the lower part of the jacket A to a point adjacent the forward end thereof. An outlet pipe 9 is screwed into an outlet port 10 located in the top of the outer side wall

member 3, adjacent the rear end of the jacket so as to provide for circulation of the cooling water.

A fluid pressure pipe 12 is mounted and extends longitudinally within the jacket A, and has its rear end connected by standard elbows 13 and 14 with a supply pipe 15 leading from any source of fluid pressure supply. The forward end of the pipe 12 is threaded into a reducing bushing 16 which in turn is threaded into one of the end openings 17 of a standard T-pipe fitting 18 which forms the mixing chamber of the burner.

The other end opening 19 of the T-fitting, which is opposite and in line with the opening 17, has a short standard pipe nipple or connector 20 threaded therein which in turn is threaded into and connects a nozzle 21 with the mixing chamber. The nozzle is provided with diverging outlet ports 22 and 75 is a specially formed fitting.

An atomizing member 23 in the form of a special forging is threaded into the center opening 24 of the T-fitting 18. The atomizer comprises a hollow body portion 25 having its one end closed by a perforated atomizing wall 26 and having tapped openings 27 and 28 in its other end and side wall, respectively. The tapped opening 27 is adapted to be normally closed by a standard pipe plug 80 29 and is provided so as to permit ready access for cleaning.

A fuel pipe 30 is connected into the opening 28 in the side wall of the atomizer by a connecting nipple 30^a and bushing 30^b, and extends rearwardly through the jacket parallel with the fluid pressure pipe 12 and is connected at its rear end by standard pipe elbows 31 and 32 with a supply pipe 33 leading from a suitable fuel supply (not shown). 95

The atomizer 23 is provided at its inner or atomizing end with an integral baffle member 34 which extends inwardly beyond the perforated atomizing end wall 26 a material distance, into the flow line of the fluid pressure to intercept the flow of fluid and prevent it striking against the atomizing end wall. If the fluid under pressure is permitted to strike or wipe the atomizing wall 26, the fuel jets would be wiped off close along the wall 26 and prevent the formation of the proper fuel jets. Therefore, it is essential that the fuel jets be free to flow a material

distance from the atomizer before coming into contact with the fluid pressure flowing at right angles thereto.

Attention is called to the fact that all 5 parts of the burner described above are standard pipe parts readily procurable on the open market in all parts of the country, except the atomizing member 23 and the nozzle 21 which parts may be made by forging or casting or may be machined from a 10 solid piece of metal. By using standard pipe fittings and pipe as described above, a burner having a low first cost and low upkeep is provided, and repair parts may be readily 15 obtained.

This burner may be used for burning any 20 of the several forms of liquid fuel. However it is particularly adapted for burning tar and when so used the fluid pressure utilized to completely atomize and mix with the tar will be steam, while when oil is used, air under pressure will preferably be used.

In operation, assuming that tar is to be 25 burned, the tar in a fluid state flows through the pipe 30 under sufficient pressure to force through the perforations in the form of fine jets or spray. The steam under pressure is flowing through the pipe 12, into the T-fitting or mixing chamber 18, and is prevented 30 from wiping the jets of fuel by the baffle 34. The fuel and steam will mix in the T-fitting or mixing chamber 18 and the pressure of the steam and its heat will combine to further break up and atomize the fuel into the form 35 of a mist or vapor, in which form it is readily combustible and will be carried out through the nozzle 21. The distance between the mixing chamber 18 and nozzle 21 is so short that recoagulation of the atomized 40 fuel and condensing of the steam is prevented.

While we have shown one preferred form of our invention, it will be understood that we do not wish to be limited to the exact details shown, since various modifications may 45 be made without departing from the scope of our invention as defined in the appended claim.

We claim—

A liquid fuel burner comprising, in combination, a tubular double-walled water jacket having both ends open to permit the free circulation of air therethrough, a standard T-pipe fitting forming a mixing chamber and mounted intermediate the ends of 55 said water jacket, an atomizer screwed into the center opening of said T-fitting, said atomizer comprising a hollow body member having a perforated end for atomizing the fuel and having its other end closed by a removable plug to permit access for cleaning, a fuel pipe connected with said atomizer, a fluid pressure pipe secured into one of the end 60 openings of said T-fittings so that the fluid under pressure will flow through said mixing chamber at right angles to the fuel entering from said atomizer, a nozzle connected with the other of said end openings of said T-fitting and terminating short of the forward end of said jacket, and a baffle 70 formed integral with and projecting from the atomizing end of said atomizer into the flow line of the fluid from said fluid pressure pipe, to prevent the fluid pressure from striking the perforated atomizing end of the 75 atomizer and thereby interrupting the flow of fuel.

In testimony whereof we have hereunto set our hands.

WENZEL H. BOEHM,
HOWARD S. COREY.
